CLAIM

The ornamental design for a computer display screen with graphical user interface for risk vector analysis, as shown and described.

DESCRIPTION

The file of this patent contains at least one drawing executed in color. Copies of this patent with color drawing(s) will be provided by the Office upon request and payment of the necessary fee.

The FIGURE is a front view of a computer display screen with graphical user interface for risk vector analysis. In the FIGURE, the broken lines showing a computer display screen and elements of the graphical user interface are included for the purpose of illustrating portions of the article and form no part of the claimed design.
